UNITED STATES PATENT OFFICE.

HENRY C. HETTELSATER, OF CANTON, OHIO, ASSIGNOR, BY MESNE ASSIGNMENTS, TO THE HOOVER COMPANY, OF NORTH CANTON, OHIO, A CORPORATION OF OHIO.

SUCTION CLEANER.

Application filed August 5, 1922. Serial No. 579,808.

To all whom it may concern:

Be it known that I, HENRY C. HETTELSATER, a citizen of the United States, residing at Canton, in the county of Stark and State of Ohio, U. S. A., have invented certain new and useful Improvements in Suction Cleaners, and do hereby declare that the following is a true and correct description of the same.

10 This invention relates in general to suction cleaners and in particular to that type of small portable machines in which provision is made for attaching a flexible hose whereby tools intended for cleaning places inaccessible to the fixed nozzle of the machine may be used. In this connection it is customary to provide some means whereby the flexible hose may be readily attached to the proper part of the suction cleaner. Such 20 means are usually referred to as "converter attachments."

An object of my invention is to provide a novel form of suction cleaner and a novel converter attachment therefor adapted to 25 be quickly and accurately attached to the suction cleaner with a minimum of effort.

Another object is to provide a suction cleaner and a converter therefor which when attached allows the suction cleaner 30 to rest upon the floor wheels and thus be readily portable.

A further object is to provide a converter attachment that may be connected directly to the source of suction of the cleaner and 35 in which the air meets no abrupt corners nor expansion chambers in the air passages before entering the fan chamber.

With the above and other objects in view, the invention consists of the improved suction 40 cleaner and converter attachment and the parts and combinations as set forth in the claims and all equivalents thereof.

In the accompanying drawings in which the same reference characters indicate the 45 same parts in all of the views:

Fig. 1 is a perspective view of a suction cleaner upside down made in accordance with my invention and adapted to receive the novel converter attachment which likewise forms part of the same invention.

Fig. 2 is a plan view of the converter attachment.

Fig. 3 is a sectional view of the converter taken on line α — α of Fig. 2.

Fig. 4 is a side elevation of the same.

Fig. 5 is a plan elevation of the pulley housing.

Fig. 6 is a side elevation of the rear supporting bracket.

Fig. 7 is an inverted plan view of the same.

Fig. 8 is a partial view of the bottom of the fan chamber illustrating details of construction.

Figs. 9 and 10 are detail views.

Figure 11 is a perspective view of a suction cleaner upside-down showing the converter attachment in place.

In the drawings, the reference numeral 10 designates the fan chamber of a suction cleaner which is provided with a discharge conduit 11 and an intake opening 12. Extending forwardly from the fan chamber and cast integrally therewith, is a suction hood 13 the open bottom of which is partially closed by a removable plate 14, secured by any convenient means, such as screws and having a front edge 15 forming the rear lip of the suction mouth 16. The suction hood is further provided on each side with forwardly and outwardly flaring walls 17, 17 which together with the rear and side walls form pockets in which the carrier wheels 18, 18 are rotatably mounted.

The rear of the machine is supported on floor wheels 19, 19 which are adjustably mounted on bracket 20.

Adjustably mounted in suitable bearings in the suction mouth is a rotatable brush 21 which is driven by a belt 22 trained over a pulley 23 on the motor shaft 24. It is to be understood, however, that my invention is not limited in any way to suction cleaners of the motor driven brush type, but is of general application.

In order to secure a passageway for the air from the open rear end of the suction hood to the intake opening of the fan chamber which will be readily removable and at the same time be capable of being conveniently and accurately replaced, I have provided a pulley housing member comprising a flat bottom portion 25, approximately parabolic in shape, the front edge formed in a straight line and adapted to snugly fit the rear edge of plate 14. Extending upwardly and outwardly from the curved edge of the bottom portion and formed integrally

therewith is a side wall 26, the top edge of which fits against the bottom wall of the fan chamber and the ends of which fit against the rear walls of the suction hood. 5 At the forward edges the side wall 26 is provided with laterally extending flanges 27, 27 on which are formed small pins 28 which fit in similarly shaped depressions in the rear wall of the suction hood in order to 10 insure proper registry of the housing member with the rest of the machine. The side wall is further provided with finger grips 29 for ease in handling and with an extension 30 at the rear top edge formed with 15 a sloping edge 31.

In order to firmly secure the housing member to the rest of the machine, I have provided a laterally sliding clamping wedge 32 formed with an enlarged portion 33 having 20 a sloping edge 34 adapted to coat with the sloping edge 31 and with a finger grip 35. This wedge 32 is guided in its lateral movement by a housing 36 secured to the bottom wall of the fan chamber and here shown 25 made integrally with the bracket 20. The housing 36 is formed with a channel 37 (see Fig. 6) the sides of which act as guides for the wedge 32, with an elongated slot 38 through which the finger grip 35 extends, and with a cut away portion 39 at the 30 front to receive the extension 30 of the housing member.

When it is desired to attach a flexible hose to the machine so that the tools may be 35 used, the housing member is detached and the converter attachment illustrated in Figs. 2, 3 and 4 is substituted in its place. The converter attachment comprises a substantially hemispherical portion 40 connected 40 with a laterally extending conduit 41 the free end of which is adapted to receive the end of the ordinary flexible hose commonly used with this type of machine. The upper part 45 of the hemispherical portion is of such a size as to register with the intake 12 of the fan chamber and is provided with a flange 42 adapted to fit snugly against the bottom wall of the fan chamber. Extending forwardly and flaring outwardly on each side 50 of the hemispherical portion is an arm 43 terminating in a laterally extending flange 44 on which is formed a small pin 45 adapted to fit in the similarly shaped depressions 55 in the rear wall of the suction hood. The arms 43 and the hemispherical portion are connected with a flange 46 the front edge of which is straight and fits snugly against the rear edge of the plate 14.

Extending rearwardly from the flange 42 60 is an arm 47 having part of its ends cut away on an angle so as to form the sloping surface 48 which is adapted to coat with the wedge 32 and thus hold the converter attachment clamped against the rear wall of 65 the suction hood.

The rear caster supporting bracket 20 and the housing 36 are mounted upon a slightly raised portion 49 of the bottom of the fan chamber 10 (see Fig. 8). This portion 49 is provided with an elongated pocket 50 70 and with a slot 51 which registers with the cut away portion 39 of the housing 36. In order to prevent any loose play or other undesired movement of the wedge 32, a curved leaf spring 52 (Fig. 10) is placed in the 75 pocket 50 and normally presses the wedge 32 against the bottom of the slot 37.

While for the sake of convenience I have illustrated my invention in connection with a suction cleaner of the vertical motor type, 80 it is to be understood that the invention is in no way limited to machines of this type but is of general application.

I claim:

1. In combination with a suction cleaner 85 comprising a fan chamber having a flat bottom wall with an intake opening therein and a suction hood having vertical rear walls, of a converter attachment comprising a hemispherical portion adapted to register with 90 said intake opening, a conduit connecting with said hemispherical portion and outwardly flaring side walls enclosing said hemispherical portion and having edges contacting with the flat bottom wall of the fan chamber and with the vertical rear walls of 95 the suction hood.

2. In combination with a suction cleaner comprising a fan chamber having a flat bottom wall with an intake opening therein 100 and a suction hood having vertical rear walls, of a converter attachment comprising a hemispherical portion adapted to register with said intake opening, a conduit connecting with said hemispherical portion and outwardly flaring side walls enclosing said hemispherical portion and having edges contacting with the flat bottom wall of the fan chamber and with the vertical rear walls of the suction hood, and means 105 for clamping the edges of the outwardly flaring side walls against both the bottom wall of the fan chamber and the rear walls 110 of the suction hood.

3. In combination with a suction cleaner 115 comprising a fan chamber having a flat bottom wall with an intake opening therein and a suction hood having vertical rear walls, of a converter attachment comprising a hemispherical portion adapted to register with said intake opening, a conduit connecting with said hemispherical portion and outwardly flaring side walls enclosing said hemispherical portion and having edges contacting with the flat bottom wall of the fan chamber and with the vertical rear walls of 120 the suction hood, and a single securing means for forcing the edges of the side walls against the bottom wall of the fan chamber and the rear walls of the suction hood. 125

4. A converter attachment for suction cleaners comprising a body portion having a discharge opening, an intake conduit connecting with said body portion, forwardly and outwardly extending side walls provided at one end with a projection adapted to be secured to a suction cleaner, and at the other end with means to insure proper registry with said suction cleaner.
- Signed at Canton, in the county of Stark, ¹⁰ and State of Ohio, this 27th day of July A. D. 1922.

HENRY C. HETTELSATER.
